INDEX

Clarence P. Hornung, Hempstead, N. Y., assignor
of one-half to Leo H. Joachim, county of New
York, N. Y.

Application May 23, 1941, Serial No. 394,747

4 Claims. (Cl. 283—38)

This invention relates generally to indexes and more particularly to the class employable with or as a folder, book, index card, letter file or index file.

It is an object of the present invention to provide economical, efficient and practical index means formed out of the body of the sheet carrying the same and readily securable to said body in operable position.

It is a further object of the present invention to provide a sheet with a substantially U-shaped cut adjacent an edge thereof to form a tongue foldable on a line connecting the ends of the cut, the tongue when folded forming a tab having a portion protruding beyond the said edge, and with at least one cut in said sheet at said edge forming oppositely bendable portions, one of the portions having overlapping engagement with the tab to lock the same in folded position.

It is yet another object of the present invention to provide a sheet with a substantially U-shaped cut adjacent an edge thereof forming a tongue foldable on a line connecting the ends of the cut against the underface of the sheet thus providing a tab having a portion protruding beyond the mentioned edge at said underface, the said tab being securable against said underface in operable position.

These and other objects of the invention will appear from the following disclosures thereof together with the attached drawing which illustrates preferred forms of embodiment thereof, and in which:

Fig. 1 is a fragmentary view of a sheet provided with cuts to form a tongue in accordance with the invention;

Fig. 2 is a similar view showing the tongue folded to form a tab;

Fig. 3 is a view similar to Figure 2 showing an alternate form of the invention;

Fig. 4 is an edge view of Figure 2 drawn to an enlarged scale;

Fig. 5 is a fragmentary detailed form of the sheet showing still another form of the invention;

Fig. 6 illustrates the invention as applied to a sheet to form an index card;

Fig. 7 is an end formed of a folder having the invention applied thereto;

Fig. 8 is a front view of a book with the cover partly broken away, illustrating the application of the invention to form index tabs for said book.

Referring to Figs. 1, 2 and 4 there is shown a sheet 10 which may represent a portion of a book, folder or letter file or an index card. Sheet 10 has a substantially U-shaped cut 11 formed

adjacent the edge 12 thereof providing a tongue 13 foldable on the line 14 connecting the ends 15, 16 of the cut 11. Tongue 13 when folded over the underface of sheet 10 forms a tab 17 having a portion 18 projecting beyond edge 12. Tab 17 is shown as having an arcuate-shaped edge 19.

At edge 12 of sheet 10 there are formed inwardly directed cuts 20, 21 having offset portions 22, 23, respectively. The portions 24, 25 of these cuts are aligned with the cuts 26, 27 of the U-shaped cut 11. The cuts 20, 21 form oppositely bendable portions 28, 29 and 30, 31 having overlapping engagement with tab 17 at its underface locking the latter in folded position as clearly seen in Fig. 2. Portions 29, 30 and the part of sheet 10 therebetween overlap the adjacent portion of tab 17 at the top face 32 of sheet 10.

In Fig. 3 which shows an alternate form of the invention, the tongue or tab 40 has a pair of ears 41 and the cuts 42 inwardly directed from edge 43 are straight. Ears 41 and portions of sheet 44 at cuts 42 adjacent thereto are in overlapping engagement thus locking the tab 40 in folded position.

The hinge line connecting the tongue to the sheet proper and about which the tongue is folded to form the extended tab, may be reinforced as shown in Fig. 5, in which, for example, the numeral 45 indicates a metallic deposit on one of the surfaces 46 of the sheet.

Fig. 6 disclosed the invention applied to an index card 50 in which a plurality of tabs 51 and locking means 52 are formed therein in a manner, for example, similar to that shown in Figs. 1, 2 and 4.

This same structure of tab and lock is shown in Fig. 7 as applied to a folder 55, the tab being indicated by the numeral 56; and in Fig. 8 as applied to a book 57, the tabs being indicated by the numeral 58.

It is understood that the forms of the invention as disclosed in Fig. 3 may be applied to the devices shown in Figs. 6, 7 and 8.

Any suitable indicia may be carried by the tabs for indexing, sectioning, separating, etc. subjects matter.

To facilitate maintaining the tab in folded condition against the sheet, spot gluing (not shown) may be employed between the tab and sheet. It will be found, however, that the locking means shown in the drawing are effective for the purpose.

It can be seen that in one embodiment of the invention the tongue 13 is struck out of the body

of the sheet adjacent the edge 12, the tongue being foldable along the line 14 parallel to edge 12, this line being at such distance from edge 12 which is less than the length of the tongue whereby to form when folded a tab having a portion protruding beyond edge 12; and that the means for securing the tab adjacent the body of the sheet comprises a pair of spaced cuts 20, 21 in the sheet at edge 12, a portion 24, 25 of the cuts being separated from each other a distance equal to the width of the tab and another portion 22, 23 of the cuts being separated from each other a distance less than the width of the tab.

Where indexes are employed particularly in books, it is customary that the index tabs or sheets be applied or inserted after the book pages are trimmed. The index made in accordance with the present invention eliminates the necessity of applying the index tabs or sheets after the book is trimmed because of the fact that the tongue is made out of the material of the sheet and then folded to form the extended tab.

The foregoing disclosures are to be regarded as descriptive and illustrative only, and not as restrictive or limitative of the invention, of which embodiments may be constructed including modifications without departing from the general scope herein indicated and denoted in the appended claims.

Having thus described the invention, what is claimed as new and desired to be secured by Letters Patent, is:

1. In a sheet a substantially U-shaped cut made in said sheet adjacent an edge thereof to form a tongue foldable on a line connecting the ends of said cut, said tongue when folded forming a tab having a portion protruding beyond the mentioned edge, and at least one cut made in said sheet at said edge, said latter cut forming oppositely bendable portions, one of said portions having overlapping engagement with said tab to lock the same in folded position.

2. In a sheet a tongue struck out of the body of said sheet adjacent an edge thereof, said tongue being folded along a line parallel to said edge, said line being at such distance from the said

edge which is less than the length of said tongue whereby to form when folded a tab having a portion protruding beyond said edge, and means for securing said tab adjacent said body, said means comprising at least one cut in said sheet at said edge, said cut forming oppositely bendable portions, one of said portions having overlapping engagement with said tab to lock the same in folded position.

3. In a sheet a tongue struck out of the body of said sheet adjacent an edge thereof, said tongue being folded along a line parallel to said edge, said line being at such distance from the said edge which is less than the length of said tongue whereby to form when folded a tab having a portion protruding beyond said edge, and means for securing said tab adjacent said body, said means comprising a pair of spaced cuts in said sheet at said edge, a portion of each of said cuts being separated from each other a distance equal to the width of said tab and another portion of each of said cuts being separated from each other by a distance less than the width of said tab.

4. In a sheet a tongue struck out of the body of said sheet adjacent an edge thereof, said tongue being folded along a line parallel to said edge, said line being at such distance from the said edge which is less than the length of said tongue whereby to form when folded a tab having a portion protruding beyond said edge, and means for securing said tab adjacent said body, said means comprising at least one extension on said tab and at least one cut in said body at said edge, said extension and the material of said body adjacent said cut being in overlapping engagement when said tongue is folded along said line.

CLARENCE P. HORNUNG.
